MAGNETOGENERATOR FOR INTERNAL
COMBUSTION ENGINES

Gustave D. Cerf, Sidney, N. Y., assignor to Bendix
Aviation Corporation, South Bend, Ind., a cor-
poration of Delaware

Application January 30, 1937, Serial No. 123,267

10 Claims. (Cl. 171—209)

The present invention relates to magneto-generators for internal combustion engines and more particularly to a double magneto in which two high tension induction coils are energized from a single rotor in conjunction with a unitary form of breaker and distributor mechanism, especially for use in connection with twin ignition systems.

It is an object of the present invention to provide a novel double magneto which is simple and compact in construction and efficient and reliable in operation.

It is another object to provide such a device which is particularly well adapted for efficient shielding against radio interference.

It is another object to provide such a device in which the various units are independently detachable for convenient inspection and adjustment.

It is a further object to provide such a device in which the high tension output cables may be arranged to enter at the sides of the magneto, thus facilitating proper enclosure and shielding, and permitting the use of shorter and more direct cable connections.

It is another object to provide such a device which incorporates a novel form of distributor mechanism which makes possible the improvement and simplification of the high tension circuits.

Further objects and advantages will be apparent from the following description taken in connection with the accompanying drawings in which:

Fig. 1 is a perspective view of a preferred embodiment of the invention showing one coil unit and the distributor and output terminal unit detached from the body of the magneto;

Fig. 2 is a vertical substantially mid-sectional view of the embodiment of the invention illustrated in Fig. 1;

Fig. 3 is a vertical substantially mid-sectional view of a second embodiment of the invention embodying principally a modified arrangement of the induction coils; and

Fig. 4 is a semi-diagrammatic representation of the electrical and magnetic circuits employed in the present invention, together with the novel form of double distributor mechanism therein employed.

Referring first to Figs. 1 and 2 of the drawings, there is illustrated a magneto comprising a frame 1 in which is journaled a drive shaft 2 as by means of bearings 3 and 4. A magnetic rotor 5 is suitably fixed on the shaft 2 between the bear-

ings 3 and 4. This rotor comprises a cylindrical permanent magnet 6 magnetized in quadrants and having pole shoes 7 incorporated therewith preferably by being embedded in the body 8 of the rotor which is formed by casting non-magnetic material in and around the magnet. The rotor is fixed on shaft 2 by any suitable means such as a clamping nut 9 which forces the rotor against a shoulder 11 on the shaft.

According to the present invention, pairs of stationary pole members 12 and 13 are fixed in the frame 1 as by being cast therein in position to cooperate simultaneously with opposite pairs of rotor pole shoes 7. High tension induction coils 14 and 15 are provided with cores 16 and 17 of highly permeable material rigidly connected to the free ends of the stationary pole members 12 and 13 respectively as by means of bolts 18 and 19. Side covers 21 and 22 are detachably mounted on the frame 1 as by means of studs 23 and 24 and are arranged to enclose coils 14 and 15 and receive the ends of cables 25 and 26 by which the primaries of the coils are grounded when it is desired to render the magneto inoperative.

A double breaker mechanism for the two coils is mounted in the upper end of the frame 1 and includes two breaker devices 27 and 28 operated by a single cam 29 suitably fixed to the drive shaft 2 for rotation therewith.

An output terminal block 31 is mounted in an end cover 32 detachably fixed to the end of the frame 1 as by means of studs 33. A circular series of terminals 34 is molded in the terminal block 31, and a pair of arcuate conductors 35 and 36 (Fig. 4) is molded therein in position to surround the terminals in spaced concentric relation therewith. Extensible conducting elements 37 and 38 are mounted in the terminal block 31 suitably connected as indicated at 39 to the arcuate conductors and arranged to project into engagement with the secondary terminals of coils 14 and 15 as shown at 41.

A distributor rotor 42 is fixed on the end of the drive shaft 2 for rotation therewith as indicated at 43 and is provided with an annular portion 44 extending into the space between the terminals 34 and the arcuate conductors 35, 36. The distributor rotor has molded therein a pair of conductors 45 and 46 (Fig. 4) having outwardly protruding ends 47 and 48 adapted to cooperate with the arcuate conductors 35 and 36, and inwardly protruding ends 49 and 51 circumferentially spaced therefrom and arranged to co-

operate simultaneously with pairs of adjacent terminals 34.

The terminals 34 are connected in pairs by means of output cables 52 to twin ignition devices 53 of the engine to be ignited, whereby each of said twin devices receives simultaneously high tension current from one of the two coils 14 and 15 in properly timed sequence as determined by the operation of the breaker mechanisms 27 and 10 28 and the distributor 42.

In the operation of the device, rotation of the drive shaft 2 in timed relation to the operation of the engine by any suitable means such as a pinion 54 causes the magnetic rotor 5 to rotate 15 whereby the flux therefrom is caused to reciprocate simultaneously through the cores 16 and 17 of the induction coils 14 and 15. The currents induced in the primaries of the coils are suitably controlled by the breaker mechanisms 27 and 28 20 whereby simultaneous secondary discharges are produced by said coils which are conducted through the extensible conductors 31 and 38 to the arcuate conductors 35 and 36 in the terminal block 31. The conductors 45 and 46 in 25 the distributor rotor 42 receive the high tension currents from the arcuate conductors 35 and 36 and transmit the same to adjacent terminals 34 from which the cables 52 transmit said currents to the ignition devices 53 of the engine.

30 In order to clarify the operation of the distributor, the twin ignition systems have been designated generally in Fig. 4 by the letters A and B, and the pairs of individual ignition circuits for the cylinders of the engine have been designated 35 I, II, III and IV, corresponding to the engine cylinders in which they are mounted. Thus the pair of devices AI and BI are arranged to ignite the first cylinder of the engine, AII and BII the second cylinder, and so on.

40 In the position of the distributor as illustrated in Fig. 4, current from system A is transmitted through conductors 35 and 45 to terminal AII, while current from ignition system B is transmitted through conductors 36 and 46 to terminal 45 BII whereby cylinder II will be simultaneously ignited by both ignition devices thereof. When the rotor has turned through an arc of 90 degrees, the conductors 45 and 46 are positioned to energize the ignition devices of cylinder III 50 through the terminals AIII and BIII, and rotation through another arc of 90 degrees similarly causes energization of ignition devices of cylinder IV through terminals AIV and BIV. It will be noted that although the distributor rotor 55 conductors 45 and 46 cooperate alternately with the arcuate conductors 35 and 36 which are incorporated in systems A and B respectively, the various terminals are always energized from the same ignition systems in regular sequence.

60 This arrangement of the output terminals in a circle within the path of the rotor conductors which transmit the high tension current inwardly from the surrounding conductors 35 and 36, permits a shortened and simplified connection to 65 the induction coils and the arrangement of the output cables 52 radially to the device without any terminals extending axially from the end cover. This greatly facilitates shielding of the magneto and simplifies installation problems.

70 In the embodiment of the invention illustrated in Fig. 3, the induction coils 55 and 56 are mounted in the side cover plates so as to be detachable therewith. This is accomplished, as there shown, by forming mounting lugs 57 on the body of the 75 coil, forming mounting pedestals 58 therefor in

the inside of the cover 59 and attaching said lugs thereto as by means of studs 61. The core 62 of the coil 55 is formed to fit snugly between the ends of the stationary pole members 63 so as to complete a magnetic path of low reluctance 5 therebetween. It will be understood that the core of coil 56 is similarly fitted between the ends of the corresponding fixed pole members 64.

The remaining elements of the structure are similar to those of the embodiment previously 10 described and are similarly numbered, and the operation of the device is the same as above set forth.

Although but two embodiments of the invention have been shown and described in detail, it 15 will be understood that other embodiments are possible and various changes may be made in the design and arrangement of the parts without departing from the spirit of the invention as defined in the claims appended hereto. 20

What is claimed is:

1. In an ignition magneto for internal combustion engines, a casing, a magnetic rotor journaled therein, oppositely arranged stator elements fixed in said casing in position to cooperate with the rotor, detachable covers for opposite sides of the casing, induction coils mounted in said covers with their cores positioned to cooperate with said stator elements and receive flux from the rotor therethrough, a detachable cap for the end of the casing, and breaker and distributor mechanism mounted in the end of the casing and actuated by said rotor, including a distributor terminal block mounted in said cap. 30

2. In an ignition magneto for internal combustion engines, a casing, a magnetic rotor journaled therein, oppositely arranged stator elements fixed in said casing in position to cooperate with the rotor, detachable covers for opposite sides of the casing, induction coils mounted in said covers with their cores positioned to cooperate with said stator elements and receive flux from the rotor therethrough, a detachable cap for the end of the casing, breaker and distributor mechanism mounted in the end of the casing and actuated by said rotor, including a distributor terminal block mounted in said cap, 40 means for conducting primary current from said coils to the breaker mechanism, and means for conducting secondary current from said coils to the distributor terminal block including conductors surrounding the terminals of the block, and means for passing current therefrom laterally inwardly to said terminals. 50

3. In an ignition magneto for internal combustion engines, a magnetic rotor, a plurality of induction coils oppositely arranged at the sides of the rotor, a distributor block having a circular series of terminals coaxial with the magnetic rotor, means including a distributor rotor surrounding said terminals for conducting high tension current from said coils radially inwardly to said terminals, and output cables radiating from said terminals. 55

4. In an ignition magneto for internal combustion engines, a magnetic rotor, a plurality of induction coils energized from said rotor oppositely arranged at the sides thereof, a distributor block having a circular series of terminals coaxial with the magnetic rotor, arcuate conductors connected to said coils surrounding said terminals, and a distributor rotor mounted to rotate with the magnetic rotor and having conductors arranged to selectively connect the arcuate conductors to said terminals. 70 75

5. In an ignition magneto for internal combustion engines, a magnetic rotor, a plurality of induction coils energized from said rotor oppositely arranged at the sides thereof, a distributor block having a circular series of terminals coaxial with the magnetic rotor, arcuate conductors connected to said coils surrounding said terminals and spaced therefrom, and a distributor rotor mounted to rotate with the magnetic rotor and having conductors located in the annular space between the arcuate conductors and the terminals, and arranged to simultaneously connect said arcuate conductors to groups of said terminals in sequence.
15. 6. A twin ignition magneto including a shaft, a magnetic rotor mounted thereon, a pair of induction coils located at opposite sides thereof, means for simultaneously energizing said coils by flux from said rotor, a cam on said shaft, a pair 20 of breaker mechanisms actuated thereby to simultaneously open and close the primary circuits of said coils, a plurality of circularly arranged output terminals, and means for simultaneously transmitting high tension current from said coils 25 to said terminals including a pair of arcuate conductors connected to said coils, and a distributor rotor mounted on said shaft having a pair of conductors arranged to connect said arcuate conductors to pairs of said terminals in sequence.
7. A twin ignition magneto including a shaft, a magnetic rotor mounted thereon, a pair of induction coils located at opposite sides thereof, means for simultaneously energizing said coils by flux from said rotor, a cam on said shaft, 30 a pair of breaker mechanisms actuated thereby to simultaneously open and close the primary circuits of said coils, a plurality of circularly arranged output terminals, and means for simultaneously transmitting high tension current from 35 said coils to said terminals including a pair of arcuate conductors connected to said coils surrounding said terminals in spaced relation therewith, and an annular distributor rotor mounted on said shaft located in the space between the arcuate conductors and the terminals, having a
- pair of circumferentially spaced conductors arranged to simultaneously connect said arcuate conductors to pairs of said terminals in sequence.
8. In an ignition magneto for internal combustion engines, a frame, a magnetic rotor journaled therein, fixed pole members in the frame cooperating therewith, side covers for the frame detachably mounted thereon, and induction coils mounted in and attached to the covers having cores adapted to cooperate with said pole members to conduct the flux from said rotor through said coils. 5
9. In an ignition magneto for internal combustion engines, a frame, a magnetic rotor journaled therein, fixed pole members in the frame 10 cooperating therewith, side covers for the frame detachably mounted thereon, induction coils in the covers having cores adapted to cooperate with said pole members to conduct the flux from said rotor through said coils, a detachable end 15 cover for said frame, a distributor terminal block mounted therein, and conductors mounted in said block detachably connected to the output terminals of said coils.
10. In an ignition magneto for internal combustion engines, a frame, a magnetic rotor journaled therein, fixed pole members in the frame 20 cooperating therewith, side covers for the frame detachably mounted thereon, induction coils mounted in and attached to the covers having cores adapted to cooperate with said pole members to conduct the flux from said rotor through 25 said coils, a detachable end cover for said frame, a distributor terminal block mounted therein, conductors mounted in said block detachably 30 connected to the output terminals of said coils, a distributor rotor fixed on the end of the magnetic rotor and arranged to selectively connect said conductors to the distributor terminals, output cables mounted in said end cover beyond 35 said conductors and extending radially therewith, and grounding cables for the coils extending radially from said side covers.

GUSTAVE D. CERF.
